UNITED STATES PATENT OFFICE.

BURWELL BOYKIN, JR., OF BEAUMONT, TEXAS.

ROTARY FOR WELL DRILLING.

Application filed May 15, 1922. Serial No. 561,178.

To all whom it may concern:

Be it known that I, BURWELL BOYKIN, Jr., a citizen of the United States, residing at Beaumont, Jefferson County, Texas, have invented a certain new and useful Improvement in Rotaries for Well Drilling, of which the following is a full, clear, and exact description, such as will enable others skilled in the art to which it appertains to make and use the same.

My invention relates to rotaries for use in drilling deep wells for oil, water, gas, sulfur, etc. More particularly the improvement has application to the gripping device used on rotary tables to hold the drive stem, in the operation of drilling.

An object of my invention is to provide a drive stem gripping device which will be easily and quickly applied to and removed from the rotary table as desired.

Another object is to provide a set of gripping rollers which will securely hold the drive stem and also allow free vertical movement of the said stem.

Another object is to provide means for securely retaining the gripping means in the rotary table.

Referring to the drawing herewith, where-in like numerals of reference are applied to like parts throughout the several views, Fig. 1 is a top plan view of my drive stem gripping device. Fig. 2 is a side elevation of the same; Fig. 3 is a side elevation taken at right angles to that shown in Fig. 2; Fig. 4 illustrates another embodiment of the gripping roller; Fig. 5 is a top plan view illustrating my invention applied to a rotary table, and Fig. 6 is a central longitudinal section on the line 6—6 of Fig. 5.

In carrying out my invention I contemplate securing in a rotary table, such as is used in well drilling, a gripping device for the drive stem, or drive stem, by means of which the drill is rotated. In the drawings I have illustrated in Figs. 1 and 2 a drive stem 7, of the usual construction. This drive stem is ordinarily square in transverse section and has a central passage 8 therethrough for the flushing fluid used in drilling. It is secured at the upper end of the drive stem and projects upwardly through the rotary table into the derrick and is supported through the usual swivel means and the cable from the crown block on the upper end of the derrick.

The drive stem is constrained to rotate with the rotary table by means of gripping rollers. In Figs. 5 and 6 I have shown a rotary table at 9 having a central removable bushing 10 therein to receive the gripping device. The bushing 10 is circular in shape and is seated within the body of the rotary, as shown in Fig. 6. The table 10 is rotated through the usual shaft and gear connecting with the gear teeth 11 on the lower marginal face of the table. The bushing 10 has a central opening 12 therein providing a squared seat for the gripping means. While I have shown this opening a square, it is contemplated that it may be of any non-circular or polygonal shape. In the type of rotary shown in Fig. 6, there is a lower pipe-supporting bushing shown at 14. Said bushing 14 is a tapered bushing circular in shape except at the upper end 15 where it is squared to fit within the seat 12 previously described. As shown particularly in Fig. 6 it is countersunk deeply within the said seat so as to allow space above the same for the gripping device. It is adapted to receive pipe engaging slips when it is desired to support the pipe. The base 16 of the gripping device has a circular tapered lower portion 17 fitting within the bushing 14, the upper plate thereof being squared as previously described. Above the base or plate 16 fitting in said opening 12, is a plate 18 overlapping the upper face of the table. This plate as shown in Fig. 5 is somewhat oblong and furnishes a mounting for the gripping rollers 19.

Said rollers 19 are each mounted upon a shaft 20, said shaft being cylindrical midway of its ends to furnish a bearing for the rollers and squared at each end as shown in Fig. 2, to fit within a slot 21 in supporting posts 22, one at each end of the shaft. The slot 21 is open at the upper end but is closed about the shaft in operation by a plate 23 fitting therein, said plate being held in position by means of a cross pin 24 extending transversely through the upper ends of each of the supporting posts 22 and said plate, and held against removal by a cotter pin 25. As shown in the drawing, the squared end of the shaft 20 is somewhat smaller than the slot in which it fits, thereby providing room at one side thereof for a plurality of square plates or shims 26. These shims furnish a means whereby the shaft 20 may be

adjusted toward or away from the drive stem 7. When it is desired to move the gripping rollers inwardly the shims are removed from the inner side of the shaft and inserted on the opposite side, thus throwing the shaft inwardly.

The rollers 19 are shaped on their outer periphery to conform to the shape of the drive stem. When the said drive stem is 10 square as shown in Figs. 1 and 5, the periphery of the rollers will have a V-shaped groove 27 therein so as to fit about the corners of the drive stem. It will thus be seen that the drive stem will be held firmly 15 between the two opposite gripping rollers 19 but the said stem will be allowed free vertical movement because of its rolling contact with the gripping device. The gripping means shown herein may be held in position 20 within the said table by means of overlapping plates or bars 28 shown in Fig. 5. To accommodate this means of holding the gripping device in its seat I have formed radially 25 extending plates 29 on opposite corners of the base 13. Each plate extends flush with the upper face portion 10 of the table to a point adjacent the edge thereof. Adjacent the outer edge of the table 9 there is an 30 up-standing lug 30 having a central opening 31 to receive the breakout pin. This lug 30 is extended laterally at 33 and provided with a transverse opening therethrough to receive the bar or pin 28 adapted to fit closely at its inner end over the outer portion of the plate 35 29 of the gripping device. The plate 28 is held against lateral movement in the lug 23 by means of a pin 32.

When the drill stem is being inserted or removed from the drill hole, the pipe gripping means must be removed out of the way. 40 The type of gripping device disclosed in this application is so constructed that it may be easily placed within its seat in the rotary table or removed as desired. When it is to be placed in position it will be inserted within 45 the seat 12 in the portion 10 of the table and secured in position by means of the bars or plates 28. The grief stem 7 will extend upwardly through the central opening in 50 the table and between the rollers 19. The rollers will be adjusted to fit firmly against the drive stem so as to hold it against rotation relative to the table. When therefore, the table is rotated it will carry with it the 55 drill stem in the usual manner. The use of rollers of this type will allow the drive stem to move freely in a vertical direction without binding. The forming of each of the rollers in the manner shown will form a 60 gripping device which will not be easily broken and will not be liable to get out of order. There are no bolts or nuts or other removable parts which may be lost during the drilling operation. Each roller is strong 65 in construction and held firmly in position

by means which may be easily removed. It therefore has many advantages over the type of gripping device now in ordinary use.

When a grief stem is used having grooves or flutes therein as shown in Fig. 4 the periphery of the gripping rollers will be shaped to fit the shape of the drive stem. Thus in Fig. 4 the rollers 19 have a central groove therein and sharp corners to fit within the vertical flutes of the drive stem and thus hold it against rotation within the gripping device. It is contemplated that in all cases the roller will be shaped to fit the drive stem which is employed by the particular make of rotary in connection with 75 which my invention is used. The advantages of this type of construction will be obvious to those skilled in the art without further description.

Having thus described my invention, what 85 I claim is new and desire to protect by Letters Patent is:

1. In a rotary device for well drilling, a rotary table having a polygonal opening therein, a gripping device for drive stems 90 having a polygonal base adapted to fit in said opening, said base having a central opening therein to allow the passage therethrough of a drive stem, two opposite rollers mounted rotatably on shafts supported on 95 said base, said rollers having peripheral grooves adapted to fit said drive stem, whereby said drive stem is held nonrotatable relative to said table.

2. In a rotary device for well drilling, a 100 rotary table having a polygonal opening therein, a gripping device for the drive stem comprising a polygonal base shaped to fit in said opening, means to hold said base removably therein, gripping rollers mounted 105 on said base, said rollers having their peripheries grooved to receive the drive stem and cooperating to fit against the sides of said stem and hold it non-rotatable relative to said table.

3. In a rotary device for well drilling, a rotary table having a non-circular opening therein in combination with a means to hold the drive stem comprising a gripping device having a base shaped to fit said opening and two gripping rollers mounted over 115 a central opening in said base, said rollers being shaped to fit the drive stem and cooperating to partially surround the same.

4. In a rotary device for well drilling, a 120 rotary table having a non-circular opening therein, in combination with a gripping device, a base on said gripping device shaped to fit said opening and having a central passage therethrough for the drive stem, a lower 125 tapered portion seating in said table, a plurality of rollers mounted adjacent said passage, the peripheries of said rollers being grooved to fit closely about the drive stem in the manner described.

5. In a rotary device for well drilling, a rotary table having a non-circular opening therein, a gripping device having a base shaped to fit said opening, a retaining plate on said table adapted to hold said base in said opening, additional means below said base to retain the same, a pair of opposite gripping rollers having their peripheries formed with V-shaped grooves to fit against 10 a squared drive stem and means to adjust said rollers to and from the said stem.
6. In a rotary device for well drilling, a rotary table, a tapered seat having a squared upper end centrally of said table, a gripping device for a drive stem having a base shaped 15 to fit in said seat, drive stem gripping rollers on said base and means to hold said gripping device removably in said table.
7. In a gripping device for drive stems, a base, two opposite rollers mounted rotatably 20 thereon, said rollers grooved to receive said drive stem, and means to adjust said rollers relative to the drive stem.

In testimony whereof, I hereunto affix my signature, this the 6th day of May, 1922.

BURWELL BOYKIN, JR.
